GEORGE H. AINGE, OF SPRINGFIELD, OHIO.

TOOL FOR TESTING SPARK-PLUGS.

1,345,337.

Specification of Letters Patent.

Patented July 6, 1920.

Application filed April 15, 1918. Serial No. 228,516.

To all whom it may concern:

Be it known that I, GEORGE H. AINGE, a citizen of the United States, residing at Springfield, in the county of Clark and State 5 of Ohio, have invented certain new and useful Improvements in Tools for Testing Spark-Plugs, of which the following is a specification.

My invention relates to improvements in 10 tools for testing spark plugs and the circuits thereof.

The object of the invention is to provide 15 a tool which will be simple in construction, effective in operation and economical in manufacture.

In the accompanying drawings:—

Figure 1 is a perspective view of the tool embodying my improvements shown attached to a spark plug.

20 Fig. 2 is another view of the tool.

Fig. 3 is a perspective view of the spark plug cleaning attachment detached.

In the drawings, 1 represents a handle, constructed of non-conducting material, 25 preferably wood with a flat upper surface. Rigidly secured to one end of the handle to the upper surface thereof is a flat metallic plate 2 formed with a contact point 2^a at one end and with a bifurcated terminal portion 2^b at the other end so that it 30 may straddle the binding post of the spark plug 3 and be clamped to the post by the binding nut 4.

Pivottally connected to the upper surfaces 35 of the handle 1 intermediate its ends is a movable switch member consisting of a metallic contact portion 5 and a handle 6 of insulating material. The binding post 7 serves as the means for pivotally connecting 40 the movable switch member and the handle together, the post being provided with a head on the under side of the handle and a nut 8 threaded on the post serving to hold the parts together. A lip 9, 45 upturned from the plate 5 prevents the nut 8 from turning and the head is slotted to receive a screw-driver or other tool so that these parts may be tightened to the desired degree. The post 7 is provided with the 50 usual binding nut 10.

In the operation of the tool, if it is desired to test the circuit for the plug, the conductor wire 11 is disconnected from the binding post of the plug and attached to 55 the binding-post 7 of the tool and the bifurcated portion 2^b of the contact plate 2 is

connected to the binding post of the plug. The movable member of the switch is then adjusted to the desired degree, such for instance as the position shown in Fig. 1, and 60 if current is passing through the wire 11 a spark will be observed between the stationary and movable members of the switch. By varying the distance between the contacts 2^a and 5 the intensity or the strength 65 of the spark may be ascertained. If desired, the circuit may be tested, when the plug is in the cylinder, by grounding the contact portion 2^b on the cylinder of the engine and making a contact between the 70 binding post of the spark plug and the contact portion 5 of the tool.

If it is desired to test the plug itself, the 75 plug is removed from the cylinder, and the connection is made as before described. By 75 then grounding the plug, it can be observed whether or not the plug is properly sparking between its points. In this test the switch on the tool may be closed, although this is not absolutely necessary providing the 80 switch members are adjusted to the proper degree.

For the purpose of cleaning the spark plug, I have shown an attachment in the 85 nature of a wire brush 12, the metallic holder 13 for the brush having a shank 14 with a sharpened end 14^a which may be fitted to a socket in the end of the handle so as to be readily removable therefrom. The sharpened end of the shank may be used 90 for scraping carbon from the porcelain of the spark plug while the brush is used for cleaning the points.

Having thus described my invention, I 95 claim:—

1. In a device of the character described, a handle of insulating material, an electric switch located thereon consisting of a stationary member and a movable member, said stationary member having a bifurcated portion to receive the binding post of a spark plug and a contact point, said movable member having a pivoted connection with said handle so as to be laterally swingable relatively thereto, said movable member also 100 having a contact point to coöperate with the contact point of said stationary member, and a binding post associated with said movable member to receive the spark plug conductor wire, said handle being extended beyond 105 said switch members and binding post a sufficient distance to permit the same to be

conveniently grasped by the hand of the operator and said movable switch member being projected in the general direction of said handle extension to allow for its ready manipulation.

2. In a device of the character described, a handle of insulating material, an electric switch located thereon consisting of a stationary member and a movable member, 10 said stationary member having a bifurcated portion to receive the binding post of a spark plug and said movable member a binding post to receive a circuit wire, said

binding post constituting a pivotal connection between said movable member and said handle, said handle being extended beyond said switch members and binding post a sufficient distance to permit the same to be conveniently grasped by the hand of the operator.

In testimony whereof, I have hereunto set my hand this 12th day of April, 1918.

GEORGE H. AINGE.
